(57) **CLAIM**

The ornamental design for an endcap for an architectural covering as shown and described.

DESCRIPTION

FIG. 1 is a perspective view of an endcap for an architectural covering.

FIG. 2 is a front view of the endcap illustrated in FIG. 1.
FIG. 3 is a rear view of the endcap illustrated in FIG. 1.
FIG. 4 is a first side view of the endcap illustrated in FIG. 1.

FIG. 5 is a second side view of the endcap illustrated in FIG. 1.

FIG. 6 is a top view of the endcap illustrated in FIG. 1.
FIG. 7 is a bottom view of the endcap illustrated in FIG. 1; and,

FIG. 8 is a perspective view of an endcap for an architectural covering that is configured to be installed on the opposite side of the covering as the endcap shown in FIGS. 1-7 (e.g., a left-side endcap as opposed to a right-side endcap), with the endcap shown in FIG. 8 being a mirror image of the endcap shown in FIGS. 1-7.

The dashed or broken lines contained within the figures represent portions of the disclosed subject matter that form no part of the claimed design.
